CORING APPARATUS

John C. Stokes, Houston, Tex., assignor to Reed
Roller Bit Company, Houston, Tex., a corpora-
tion of Texas

Application March 7, 1951, Serial No. 214,357

6 Claims. (Cl. 255—72)

1

This invention relates to new and useful improvements in coring apparatus and relates particularly to coring apparatus of the removable type.

As is well known, it is the general practice to employ a removable core barrel for cutting a core in advance of the drill bit with the particular advantage of the removable barrel being that the core may be cut and retrieved without removing the drill pipe and bit from the bore. The removable-type core barrel ordinarily extends through an axial bore or opening in the drill bit when in operative position and in the past this bore or opening has been of a constant diameter which is substantially equal to the external diameter of the core barrel. It has been found that during the coring operation and while the core barrel is extending through the bore or opening in the drill bit, mud, cuttings and other extraneous matter may enter the space between the exterior of the core barrel and the wall of the bore or opening in the drill bit and may become packed therein, with the result that the core barrel becomes stuck within said bore or opening and is difficult to remove.

It is, therefore, one object of this invention to provide an improved coring apparatus wherein sticking of the removable core barrel within the bore or opening of the drill bit is obviated to assure that said core barrel may be readily removed when desired.

An important object is to provide the drill bit with an axial bore or opening having its lower portion of a diameter substantially equal to the external diameter of the core barrel and having its upper portion enlarged outwardly toward the upper end thereof, whereby when the core barrel is extending therethrough said barrel is in substantial engagement with the lower portion of the wall of the bore but is out of contact with the remainder thereof; the enlargement of the upper portion of the bore facilitating removal of the core barrel even though foreign matter may have accumulated in the area between the barrel and the wall of the bore.

A further object is to provide the wall of the axial opening or bore of a drill bit, through which a removable core barrel extends, with longitudinal passages which are of such shape and dis-

position that removal of the core barrel is readily accomplished when desired.

5 A still further object is to provide in the bridge support of a drill bit an axial tapered opening extending therethrough, with the enlarged portion of the opening at the upper end of the support, the wall of the opening being formed with longitudinal passages which permit circulation past a core barrel extending through the opening, whereby the possibility of said core barrel sticking within the opening in the event that foreign matter accumulates in the space between the barrel and wall of the opening is obviated.

10 Still another object is to provide an apparatus, of the character described, wherein the core barrel is properly supported when in core-taking position but yet is readily removable at any time without danger of sticking.

15 The construction designed to carry out the invention will be hereinafter described together with other features thereof.

20 The invention will be more readily understood from a reading of the following specification and by reference to the accompanying drawings forming a part thereof, wherein an example of the invention is shown, and wherein:

25 Figure 1 is a vertical sectional view of an apparatus, constructed in accordance with the invention.

30 Figure 2 is a vertical sectional view, taken on the line 2—2 of Figure 1.

35 Figure 3 is a sectional view of the bridge structure of the outer bit, illustrating a tapered bore.

Figure 4 is a sectional view, taken on the line 4—4 of Figure 3, and

40 Fig. 5 is a cross-sectional view, taken on the line 5—5 of Figure 4.

45 In the drawings, the numeral 10 designates an outer core bit which is attached in the usual manner to the usual drill string or pipe 11. The bit is illustrated as a roller type bit having a pair of diametrically opposed outside cutters 12 and a pair of diametrically opposed inside cutters 13. The usual bridge 14 is disposed between the cutters and is formed with an axial bore 15 extending therethrough. The details of construction of the bit and the cutters is subject to variation.

50 A core barrel 16 having a cutter head 17 is adapted to be inserted within the lower portion of the drill string with the cutter head 17 being

adapted to extend downwardly through the axial bore 15 in the bridge 14. A suitable guide or bearing collar 18 having vertical fluid passages 19 is mounted within the upper portion of the bit and a portion 18a of the bore of this collar engages the upper portion of the cutter head 17. The core barrel is of the removable type and is adapted to be lowered in position to cut a core when desired. Ordinarily this core barrel is dropped into position and removed by means of a wire line, and it has been the practice in the past to form the axial opening 15 in the bridge 14 of a constant diameter which is substantially equal to the external diameter of the core head 17. It has been found that where the bore of the opening 15 is of a constant diameter, mud and cuttings tend to accumulate between the external surface of the cutter head 17 and the wall of the opening 15 with the result that removal of the core barrel and cutter, after the coring operation is complete, is difficult.

In carrying out the present invention the opening 15 which extends through the bridge 14 has a relatively short section at its lower portion, indicated at 20, formed of a constant diameter which is adapted to engage the external surface of the cutter head 17. Above the constant diameter section 20 the wall of the bore or opening 15 is tapered or enlarged outwardly toward the upper end of the bridge, this tapered wall portion being indicated at 21. When the core cutter head 17 is extending through the opening 15 of the bridge the section 20 at the lower portion 20 of said opening engages the external surface of the cutter head and functions as a guide and support for said head. Above the section 20 an annular tapered space, indicated at A in Figures 1 and 2, is provided, said space being formed between the external surface of the cutter head 17 and the inclined or tapered surface 21 of the bore of the bridge.

A plurality of longitudinally extending recesses or grooves 22 may be formed in the wall of the bore or opening 15 and these recesses establish communication between the tapered annular space A and the area below the cutter head. It is noted that the grooves or recesses permit circulation past the core barrel extending through the opening but if desired, said grooves may be omitted.

In the use of the apparatus it will be evident that when the core barrel 16 and its cutter head 17 are positioned within the bit as shown in Figure 1, the cutter head is supported at its lower end by the lower section 20 within the lower portion of the opening or bore 15, while the upper end of the cutter is supported by the bearing surface 18a of the collar 18 within the upper end of the bit. Extending upwardly from the lower bearing section 20 is the annular space A, the upper end of which is in communication with the area below the fluid passages 19 in the bit. Thus, during the coring operation any mud or cuttings which might accumulate within the opening or bore 15 between the outer surface of the cutter head 17 and the wall of the bore will be washed downwardly within the annular space A and if the grooves 22 are employed then through the said grooves into the area below the bridge. Thus, the construction is such that an accumulation of mud, cuttings or other extraneous matter in the area between the outer surface of the cutter head 17 and the wall of the bore 15 is prevented. Furthermore, if any cuttings or extraneous matter do accumulate within this space, 75

the tapering or enlarged upper end of the bore 15 will permit the cutter head to be easily removed upwardly from within the bore and without any binding or sticking of the cutter head within said head. The arrangement thus assures that the core barrel and its cutter head may be readily removed whenever desired after the coring operation is complete. As has been noted, the particular details of construction of the bit form no part of the present invention and the same may be applied to any standard type of core bit now on the open market and usable with removable core taking equipment.

Although it is desirable that the upper portion of opening 15 be tapered or gradually enlarged, it is pointed out that this upper portion could be of a constant diameter which would be larger than the diameter of the section 20. This would make the space A an annular enlarged space about the core barrel rather than tapered as shown. It would also be possible to form the opening of the same diameter throughout its entire length, which diameter would be substantially equal to the external diameter of the cutter head; in such case the longitudinal grooves or recesses 22 would extend throughout the length of the bore of the opening to provide circulation past the core head.

The foregoing disclosure and description of the invention is illustrative and explanatory thereof and various changes in the size, shape and materials, as well as in the details of the illustrated construction may be made, within the scope of the appended claims, without departing from the spirit of the invention.

Having described the invention, I claim:

1. The combination with a removable core barrel of a drill bit having a transverse bridge member for supporting the cutters of the bit with a space above said bridge member in which formation cuttings from the cutters may accumulate, said bridge member having an axial opening therein through which the removable core barrel is adapted to extend and the upper portion of said opening being enlarged in diameter, whereby said core barrel may be removed from the bit even though cuttings may accumulate in said axial opening exteriorly of said core barrel.

2. The combination with a removable core barrel of a drill bit having a transverse bridge member for supporting the cutters of the bit with a space above said bridge member in which formation cuttings from the cutters may accumulate, said bridge member having an axial opening therein through which the removable core barrel is adapted to extend, said opening having its lower portion of a constant diameter and having its upper portion gradually tapered outwardly from said constant diameter portion to the upper end thereof, whereby said core barrel may be removed from the bit even though cuttings may accumulate in said axial opening exteriorly of said core barrel.

3. In a rotary drilling bit having therewith a removable core barrel, a bit body, cutters mounted on said body, a transverse bridge member disposed between the cutters for supporting same in conjunction with said bit body, said bridge member and said cutters having a space thereabove in which cuttings, slush and the like may accumulate, said bridge member having an axial opening through which the core barrel is adapted to extend, and the upper portion of said opening being enlarged in diameter, whereby said core barrel may be removed from the bit even though cut-

tings may accumulate in said axial opening exteriorly of said core barrel.

4. The drilling bit as set forth in claim 3, wherein said bit body has an axial bore with a portion for vertically aligning the core barrel, said portion being spaced above said bridge member.

5. The drilling bit as set forth in claim 3, wherein said bit body has slush passages therein with the discharge ends thereof disposed above said space, whereby the slush is supplied into said space above said cutters and said bridge member.

6. The structure set forth in claim 2, including longitudinal circulation grooves radially spaced in the wall of said axial opening of said bridge

member to allow circulation past the core barrel when it is in said opening.

JOHN C. STOKES.
